FIG.5

Des. 230,232

PAGE 2

FIG. 4

FIG. 1 is a perspective view of a portable carrying case showing our new design in closed condition;

FIG. 2 is a perspective view thereof with the legs in unfolded position;

FIG. 3 is a perspective view thereof in an upright position with the walls partially erected;

FIG. 4 is a perspective view thereof in an upright position with all the walls erected; and

FIG. 5 is a cross-sectional view taken along line 5—5 of FIG. 1 with portions omitted for clarity of illustration.

We claim:

The ornamental design for a portable carrying case, as shown and described.
